(57) **CLAIM**

The ornamental design for a lid assembly with a reclosable drink opening, substantially as shown and described.

DESCRIPTION

FIG. 1 is a top perspective view of the lid assembly of this invention with the sliding member thereof in its closed position;

FIG. 2 is a top view of the lid assembly of FIG. 1;

FIG. 3 is a view in elevation of the lid assembly of FIG. 1 along line 3—3 of FIG. 2;

FIG. 4 is a top view of the sliding member of the lid assembly of this invention;

FIG. 5 is a bottom perspective view of the sliding member of FIG. 4; and,

FIG. 6 is a top perspective view of the sliding member of FIG. 4.

The portions shown in broken lines are included to show environment and form no part of the claimed design.
